US00D593031S

(12) **United States Design Patent**
Miyatake et al.

(10) **Patent No.:** US D593,031 S
(45) **Date of Patent:** ** May 26, 2009

(54) **POWER SUPPLY ADAPTER**

(75) Inventors: **Junichiro Miyatake**, Kyoto (JP);
Kazuumi Otani, Kyoto (JP)

(73) Assignee: **Nintendo Co., Ltd.**, Kyoto (JP)

(**) Term: **14 Years**

(21) Appl. No.: **29/326,259**

(22) Filed: **Oct. 15, 2008**

(30) **Foreign Application Priority Data**

Apr. 15, 2008 (JP) 2008-009597

(51) **LOC (9) Cl.** 13-02

(52) **U.S. Cl.** D13/110

(58) **Field of Classification Search** D13/110,
